CAN OPENER

William J. Fortune, Elkhart, and Charles T.
Fortune, Grimes, Iowa

Application May 21, 1952, Serial No. 289,072

3 Claims. (Cl. 30—6.1)

1

Our invention is a novel mounted can opener for opening cans containing flowable materials and for venting them simultaneously to provide for access of air to the interior of the can as the flowable material is removed from the can.

Some well known openers are provided with a hook arrangement that engages the bottom of the lip or rim of the can. The can rim becomes then a fulcrum that permits the cutter of the opener to be forced down through the can top by manual force applied to the handle of the opener. Since the can is the fulcrum as well as the unit being operated upon, it must be securely held by the operator. Sometimes it is difficult to hold the can steady enough to prevent some spilling. This is particularly true when the can opener is dulled from any cause such as long use or corrosion. Considerable effort is necessary to puncture the can lid in the first place, but once the top is fractured a little, the balance of the cutting requires relatively little pressure. The sudden reduction in pressure requirements causes the operator to be thrown off balance and the can is frequently jerked while the person opening the can is regaining control of the situation. This jerking usually causes some spilling which is not sufficient to be serious from the stand point of quantity lost, but it is undesirable. The cans are unpleasant to handle when the contents have spilled over onto the exteriors. Spilling of the contents of the cans is to be avoided when possible, obviously.

These small unmounted openers are rather slow for use in large operations such as restaurants, hotels, or at large group picnics. Not only must the operator proceed with caution, but the openers lack a reference means to align them with the cans rapidly. Frequently, some little time is lost in trying to get the opener. At an informal gathering such as a picnic, several openers may be provided and people permitted to open their own cans. This may not be desirable if some control over the quantities of cans used by any one person is intended. Also, of course, in more formal surroundings, consumers cannot be expected to open their own cans. Furthermore, during periods of rush business, a rapid means of opening cans is essential, since much of the food value of canned fruit and vegetable juices may be lost if the cans are opened in anticipation of rush periods. Still further time is lost in using the conventional beer can or like opener in that the device must be operated twice for each can opened if a smooth pouring action is to be obtained. The major opening in the can from

2

which the flowable material is poured is made with one cut. A second hole must be punched, however, to provide an air vent. Pouring can be accomplished without this vent, but the material in the can will flow in sudden bursts as distinguished from a steady flow if no vent is provided. Usually two cuts are made to insure smooth pouring. It is also important that the air vent be placed a substantial distance from the pouring cut.

In view of the foregoing, therefore, it is the principal object of our invention to provide a can opener for opening cans containing flowable materials that opens such cans rapidly and efficiently.

It is a further object of our invention to provide a can opener that supports cans while they are being opened.

It is a further object of our invention to provide a can opener that cuts an air vent in the can at the same time the pouring cut is made.

It is a further object of our invention to provide a can opener for opening cans containing flowable materials that minimizes the danger of spilling the contents of the can being opened.

These and other objects will be apparent to those skilled in the art.

Our invention consists in the construction, arrangement, and combination of the various parts of the device, whereby the objects contemplated are attained as hereinafter more fully set forth, and specifically pointed out in our claims, and illustrated in the accompanying drawings, in which:

Fig. 1 is a perspective view of our can opener mounted on a surface.

Fig. 2 is a side elevation view of our can opener. Broken lines illustrate an adjusted position of the cutter lever. Dotted lines illustrate an adjusted position of the can support and vent cutter. A can is shown in cross section to more clearly illustrate the operation of the device in opening a can.

Fig. 3 is a cross-sectional view of our can opener taken on the line 3—3 of Fig. 2, and

Fig. 4 is an enlarged fragmentary vertical sectional view of our can opener taken on the line 4—4 of Fig. 3. Broken lines illustrate how the can support is released for lowering.

Referring to the drawings, we have used the numeral 10 to designate a supporting surface to which the can opener supporting brackets 12 and 14 are secured by any suitable means such as the screws 16. To these brackets is secured the opener frame 18. The frame is rigidly se-

cured to the brackets in our illustrated structure by any suitable means such as the rivets 20. The frame or body 18 supports the can table 22 which is merely a platform adjustable on the frame. Any suitable means for providing this adjustment may be used. Our illustrated structure is a very simple one that is considered excellent for that reason. An opening 24 that fits the configuration of frame 18 is provided in the can table or support 22 and the rear portion of this opening has an element 26 secured thereto which spreads the pressure or load exerted on the back of the frame over a large area. At the lower front of the opening, a dog or pawl like member 28 is formed which engages notches 30 formed in the frame when the table 22 is in a horizontal position. The table will be held in a given position as long as the dog engages the notches. As soon as the outer end of the table is raised, however, as shown in Fig. 4, the table may be raised or lowered. Downward pressure on the table, within the limits of its strength only serves to secure it at its assumed position more effectively.

The top of frame 18 is formed into the opposed pierced ears 32 and supports the axle 34 on which is pivoted the cutter arm 36. A spring 38 yieldingly urges the arm 36 upward. The arm 36 is provided with a stop member 40 which limits the downward movement of arm 36 so that cutter 42 will not over travel and puncture the side of can 14 as shown by the broken lines in Fig. 2. The stop member 40 prevents excessive downward movement of the lever 36 by engaging the edges of the frame 18 at a point adjacent to the pierced ears 32. The cutter lever or bar 36 carries also the can venting cutter or punch 46. This cutter is adjustably mounted on the cutter lever by means of a sleeve 48 and a set thumb screw 50 secures the punch at the correct position for venting the particular size of can being opened. The end of the lever may be provided with a suitable knob or handle elements 52 to facilitate drawing the arm down. A can stop 54 limits both inward and upward movement of the can top as shown in Fig. 2.

The use or operation of our opener is very simple. The can is merely placed on the table or support and the support is adjusted upward until the can rim strikes the stop member 54. Handle 52 is grasped and lever 36 forced downward to cause the cutter and punch to open and vent the can in a single swift motion. As soon as the can is open, the handle is released and the handle is raised by spring 38 to its upward position. The can is then easily removed and a new can inserted. Each can is opened in a manner of seconds and there is no danger of spilling. As the fulcrum for the opener is on the frame and does not bear on the can, there is no danger of upsetting the can or spilling the contents. Only one 60 operation cuts and vents the can as distinguished from two operations with the usual can opener used to open cans containing flowable materials. It is much quicker and easier to align the can on our opener than to properly position the old type of "beer" can opener on a can rim. The can stop 54 prevents the can from being moved by the retraction of cutter bar and also holds the can from extending excessively far toward the opener frame 18. From the foregoing, it should be clear that we have invented a novel can opener for cans containing flowable materials that accomplishes the objects of our invention.

Some changes may be made in the construction and arrangement of our can opener without de-

parting from the real spirit and purpose of our invention, and it is our intention to cover by our claims, any modified forms of structure or use of mechanical equivalents which may be reasonably included within their scope.

We claim:

1. In a can opener, a frame, a means secured to said frame for mounting it on a supporting member in a vertical position, a lever hingedly secured to said frame, a cutter rigidly secured to said lever, a can supporting means secured to said frame and extending therefrom in a horizontal position and under a vertical projection of said lever, and a can stop secured to said frame and extending over said can supporting means near its effective edge; whereby said can stop engages the rim and side of a can resting on said can supporting means to hold said can near its top against vertical movement and lateral movement in the direction of said frame; said can stop being positioned below the hinge point of said lever and laterally between the hinge point of said lever and the said cutter secured to said lever.

2. In a can opener, a frame, a means secured to said frame for mounting it on a supporting member in a vertical position, a lever hingedly secured to said frame, a cutter rigidly secured to said lever, a plurality of spaced apart teeth on said frame, a can supporting table embracing said frame and normally extending in a horizontal position therefrom, a dog on said table near the portion of said table that is adjacent said teeth; said dog normally engaging said teeth to hold said table at a given altitude relative to said frame, and a load spreading element secured to said table near the portion of said table that embraces said frame and on the opposite side of said frame from said dog and teeth; said load spreading element extending substantially farther above the top plane of said table than below the bottom plane of said table.

3. In a can opener, a frame, a means secured to said frame for mounting it on a supporting member in a vertical position, a lever hingedly secured to said frame, a stop means on said lever that engages said frame to limit movement of said lever in one direction, a cutter rigidly secured to said lever, a punch secured to said lever at a point longitudinally spaced from said cutter, a can stop secured to said frame near the point of hinged attachment of said lever, and a can supporting means secured to said frame and extending therefrom in a horizontal position and under a vertical projection of said lever.

WILLIAM J. FORTUNE.
